Primary Examiner — Keli L Hill*Assistant Examiner* — Harold E Blackwell, II(74) *Attorney, Agent, or Firm* — Sheridan Ross P.C.(57) **CLAIM**

The ornamental design for a floor underlayment, as shown and described.

DESCRIPTION

FIG. 1 is a top perspective view of a floor underlayment according to my new design;

FIG. 2 is a bottom perspective view of the floor underlayment of FIG. 1;

FIG. 3 is a top plan view of the floor underlayment of FIG. 1;

FIG. 4 is a front elevation view of the floor underlayment of FIG. 1, which is identical to the back elevation view, the right elevation view, and the left elevation view; and,
FIG. 5 is a bottom plan view of the floor underlayment of FIG. 1.

The broken lines show portions of the floor underlayment which form no part of the claimed design.
